UNITED STATES PATENT OFFICE.

BENNET OLSON, OF GLENCOE, MINNESOTA, ASSIGNOR OF ONE-HALF TO WILLIAM C. BURTMAN, OF WASECA, MINNESOTA.

PUMP MECHANISM.

1,017,992.

Specification of Letters Patent. Patented Feb. 20, 1912.

Application filed April 25, 1911. Serial No. 623,221.

To all whom it may concern:

Be it known that I, BENNET OLSON, a citizen of the United States, residing at Glen-
5 coe, in the county of McLeod, State of Min-
nesota, have invented certain new and use-
ful Improvements in Pump Mechanisms;
and I do hereby declare the following to be
a full, clear, and exact description of the
invention, such as will enable others skilled
10 in the art to which it appertains to make
and use the same.

My invention relates to new and useful
improvements in pump mechanisms and
more particularly to that class of double
15 stroke pump operating devices.

The primary object of my invention is the
provision of a pump operating mechanism
in which the pump rod will be reciprocated
on manually swinging the operating handle
20 of the pump in one direction, whereby a
double stroke of the pump rod is attained
with a minimum amount of leverage.

Another object of my invention is the pro-
vision of a pump operating mechanism in
25 which the plunger is raised and lowered
within the pump tubing by a quick and uni-
form motion, and where the pump actuatin-
g mechanism may be so adjusted as to
lengthen or shorten the stroke without dis-
30 mantling the parts of the pump, thus obviat-
ing all subsequent leakage which is usually
caused in a pump which has been taken
apart in order to adjust the pump rod. And
a still further object of my invention is the
35 provision of a pump operating mechanism
adapted to be used in connection with all
types of single stroke pump rods, thus
adapting them to effect a double stroke, the
pump operating mechanism being so con-
40 structed as to enable the same to be used in
connection with pumps of all forms and for
all purposes.

With these and other objects in view the
invention consists in the construction, com-
45 bination and arrangement of parts which
will be hereinafter more fully described,
illustrated in the accompanying drawings
disclosing a preferred embodiment of my in-
vention and pointed out in the appended
50 claim.

In the drawings in which similar refer-
ence numerals designate corresponding parts
throughout, Figure 1 is a side elevation of
a pump with my operating mechanism ap-
55 plied thereto showing the same at the be-

ginning of the stroke. Fig. 2 is a front eleva-
tion thereof. Fig. 3 is a side elevation
partially in section showing the position of
the pump operating mechanism at the mid-
dle of the stroke. Fig. 4 is a like view 60
showing the position of the mechanism at
the end of the stroke.

I have illustrated my improved pump ac-
tuating mechanism which as a whole is des-
ignated by 1 as secured to and supported 65
by the customary form of pump casing 2,
the supporting means consisting of the two
members 3 and 4 of a split collar 5 adapted
to be secured around the top of the pump
casing 2 by means of bolts 6 passed through 70
the outwardly extending ears 7. Each of
the members 3 and 4 is provided with an up-
wardly extended member 8 terminating at
their upper ends with the inwardly directed
portions 9 which are provided with laterally 75
extending ears 10 adapted to be secured to-
gether by means of bolts, rivets or other pre-
ferred fasteners 11. A pump rod here des-
ignated as 12 has one end extended up-
wardly from the pump casing and is recip- 80
rocally mounted in this frame with its free
end extending above the terminals of the
side members 3 and 4, these terminals be-
ing adapted to form a bearing for the rod.
A helical spring 13 surrounds the extended 85
portion of the pump rod with its lower end
resting upon this bearing and its upper end
resting against a slidable collar 14 which
is mounted upon the pump rod 12 and se-
cured in adjusted position by means of the 90
set nut 15. A second collar 16 similar in
construction to the first but provided with
two oppositely extending studs 17 is also
mounted upon the pump rod, between its
upper and lower bearing and secured in 95
place by a set nut 18.

A pair of bell crank levers 19 substan-
tially right-angular in shape and with the
arms 20 and 21 are pivotally mounted on
the inner sides of the side members 3 and 4 100
by means of studs 22 formed upon the ex-
tended portion 23 of the arms 20, said studs
being adapted to be inserted in the aligned
apertures 24 and 25 tapped in the lower por-
tions of the side members 3 and 4. 105

The upper ends of the arms 20 are bifur-
cated to form elongated forks 26 the sides of
which are provided with a series of aligned
bolt receiving apertures. A pair of links 27
are rotatably secured by one end to the studs 110

17 of the collar 16, the ends of said studs being bored to receive suitable securing means such as split pins 28. The other ends of these links are pivotally secured between 5 the bifurcated member of the lever arm 20 by means of bolts or other preferred securing means 29.

The ends of the arms 21 of the bell crank levers are enlarged to form the sector shaped 10 terminals 30 which are provided with a series of apertures 31. The arms 21 are also provided with an aperture 32, and a pump handle 33 is secured between the arms 21 by means of a bolt 34 and an adjusting pin 35, said adjusting pin in connection with the 15 apertures 31 providing means whereby the handle may be secured at any desired angle to the lever arms 21.

The operation of the pump is easily understood by referring to Figs. 1, 3, and 4 of 20 the drawings and from them it will be seen that as the handle 33 is raised it acts through the medium of the bell crank levers and the connecting links to raise the pump rod, 25 which action is continued until the pump handle has been raised to a position at right angles to the pump, when a further raising of the handle will lower the pump rod to its original position. Upon the reverse stroke 30 of the pump handle the pump rod is again raised and lowered in the same manner. The spring 13 is compressed by each downward stroke of the pump rod 12 and thus stores up energy to assist in the upward 35 raising of the pump rod.

It will be seen that by means of the spaced apart bolt receiving apertures provided in the forked ends of the lever arms 20 I have

provided a simple and effective means by which the length of the stroke may be 40 readily regulated. It will also be seen that the means employed in adjusting the pump handle 23 are such, that the handle may be readily adjusted without disconnecting it from the pump.

It will be seen from the above that I have provided a simple and effective operating mechanism for use with double stroke pumps, and that this mechanism may be used upon all pumps in which a reciprocating pump rod is used and for all purposes to which pumps of that character may be adapted.

What I claim is:—

A pump actuating mechanism, comprising 55 a frame adapted to be secured to a pump casing; a pump rod reciprocally mounted in said frame, a collar adjustably secured to said pump rod and provided with oppositely disposed trunnions, a pair of bell crank levers having outwardly directed trunnions intermediate their length, said trunnions being journaled in the sides of the frame, links adjustably connecting one arm of each of 60 said levers with one of the trunnions of said 65 collar, a pump handle pivoted by one end between the other arm of said lever, and means for additionally and adjustably securing said handle between said lever arms.

In testimony whereof, I affix my signature, in presence of two witnesses.

BENNET OLSON.
